UNITED STATES PATENT OFFICE.

HENRY W. ALLPORT, OF CHICAGO, ILLINOIS.

POCKET STOVE.

Application filed April 7, 1919. Serial No. 288,190.

To all whom it may concern:

Be it known that I, HENRY W. ALLPORT, a citizen of the United States, residing in Chicago, in the county of Cook and State of Illinois, have invented a new and useful Improvement in Pocket Stoves, of which the following is a specification.

This invention relates in general to slow burning heaters and has more particular reference to heaters of this character in which a charge of material slowly combustible is adapted to give off a relatively mild heat for a prolonged period.

The invention will hereinafter be described as embodied for the purposes of illustration in a pocket or hand warmer, although it will be manifest that it may be used in a considerable number of other connections and in fact wherever a prolonged warmth or low heat is desired.

A principal object of this invention is the provision of a heater of this general character, the parts of which will be so constructed and arranged that the fuel may be provided in solid form and slow combustion at the same time maintained with certainty.

A further and highly important object of the invention is the provision of a fuel material for heaters of this character, which may be provided in such solid form and which will continue even combustion at an extremely slow rate.

Another highly important object of the invention is the provision of a heater of the character described, which will not require a fuel that will soil the hands of the user and which may be readily charged and recharged by merely striking a solid stick as one would an ordinary match and positioning it thereafter in place within the heater.

Another object of the invention is the provision of a heater of this character, which will not permit overheating of the metal, which will readily adapt itself to the intended use, i. e., the pocket or the hand, and which will be of strong and sturdy construction and without delicate parts likely to require repair or replacement.

Other objects and advantages of the invention will be apparent as it is better understood from the following description when considered in connection with the accompanying drawings which illustrate a present preferred embodiment of my invention.

Referring to the drawings,

Figure 1 is a view of a pocket heater in which my present invention is incorporated for the purposes of illustration.

Fig. 2 is a similar view showing the container without its outer fabric covering;

Fig. 3 is a transverse sectional view through the same;

Fig. 4 is a transverse sectional view similar to Fig. 3 through the container body or shell.

Fig. 5 is a vertical sectional view through the heater showing a charge in place;

Fig. 6 is a perspective view of the fuel support; and

Fig. 7 a like view of a charge of fuel.

My invention contemplates the provision of a fuel in a stick, or other solid form, as counter distinguished from the loose material usually used in devices of this character in the past and which when even used in cartridge form soils not only the hands of the person charging the heater but also surrounding objects. To this end I have provided a heater particularly adapted to receive a stick charge and to maintain the combustion thereof after the charge is ignited.

The form of the invention shown on the drawing, being particularly adapted for pocket use comprises an outer shell or container of sheet metal 11, oval in cross section and having a plurality of perforations 12 at the two sides of greater curvature. It is closed at its bottom with any suitable closure 13 and in the finished heater at the top with a closure 14, having a nozzle 15 through which the charge may be inserted and adapted to receive a cap 16. Within this body is secured a fuel support, shown in perspective in Fig. 6. This support is preferably square in cross section and consists of four sheets of metal each bent longitudinally at 17 along a middle line the sheets being seamed together at their edges at 20 to provide inwardly extending protuberances or ribs for a purpose to be presently described. This construction provides an elongated body, square in cross section, and at the sides of this body flanges 17' are bent inwardly to maintain the burning end of the charge elevated above the bottom of the shell or container when in upright position. This fuel support is positioned in the shell of the container before the top closure is secured in place and it preferably

fits closely at its sides 18 to the adjacent sides of the shell and between the two sets of perforations 12. To dispose the flange 17' easily at the desired height the sides 18 5 are extended downwardly therebelow forming legs 19.

The entire shell is incased in an asbestos insulating sheet 21, which is in turn covered by a fabric preferably of knitted material 10 22 having a soft surface against the asbestos and a hard surface outside. The cap is preferably also provided with this covering material. The charge in the present instance consists of a stick cylindrical in form and 15 indicated generally at 31. One end is rounded, as indicated at 32, and a channel or passageway 34 is provided from end to end. In the end of this passageway at the round end of the stick is provided an igniting material 35 carrying a striker cap 36, such igniting material and striker being of the general character and material of a wind match. The material of the stick or solid charge is preferably composed of a mixture 25 of carbonaceous material, as for example, charcoal; binders and combustion retardants, as for example, asbestos fiber and gum tragacanth, a rapid oxygen producing agent for oxidizing, as for example, potassium 30 nitrate and a slower oxidizing agent, as, for example, manganese dioxide. A deodorizing agent, as for example, powdered camphor may also be incorporated if desired. These materials are mixed in suitable 35 proportions, an excellent formula being—
 (a) Powdered or granulated hardwood charcoal 100 grams.
 (b) Asbestos fiber 1 gram.
 (c) Gum tragacanth 10 grams.
 40 (d) Manganese dioxide C. P. 10 grams.
 (e) Camphor. Mix thoroughly and add—
 (f) Potassium nitrate 10 grams, dissolved in enough water (warm) to make 110 c. c.

45 This product is thoroughly mixed and finally results in a gummy, doughlike mass which is vigorously kneaded and forced through a smooth bored tube of appropriate diameter and equipped with a mandrel. 50 The resulting stick is somewhat plastic and is then thoroughly dried. A charge of this character is particularly adapted to be burned in the container already described, which is designed to maintain an even and 55 slow rate of combustion under all conditions. The structure being ignited, the stick is positioned, the ribs or protuberances 20 holding the stick away from the side walls of the fuel support and away also from the container. These ribs provide passageways 60 about the fuel charge so that the fuel support acts as a flue. The maintenance of a proper kindling temperature with a restricted supply of oxygen and the regulation of 65 the rate of combustion depends in large

measure upon the temperature of the air of combustion and the arrangement just described gives to the air of combustion the temperature by preheating in desired amount and as it comes. The preheating 70 occurs also if the container be placed on its side or in other positions for the hot gases rising will draw in from the opposite side a certain amount of fresh air for combustion which will itself be preheated before entering into the flue even if entrance be had at both ends at the same time which might occur were the heater to lie on its side. It has been found that the heater acts well in any position it may be given. The oxidizing agents provide a portion of the oxygen and in connection with the retardants act to provide an internal control for the rate of combustion; the rapid oxidizing agent acting while the burning portion of the stick 80 is in the more compressed form to carry on the combustion and the slower oxidizing agent acting to complete it as the material loses its compact form. The retardant not only retards the rate of combustion but also 85 confines it to a desired zone, i. e. at the ignited end of the stick so that the combustion is slow and progressive.

90 It is thought that the invention and many of its attendant advantages will be understood from the foregoing description, and it will be apparent that various changes may be made in the form, construction and arrangement of the parts without departing from the spirit and scope of the invention 95 defined in the claims or sacrificing any of its material advantages, the form hereinbefore described being merely a preferred embodiment thereof.

100 I claim:

1. A slow combustion heater and a fuel therefor, said heater comprising a fuel holder for a solid fuel and having air passages directing and controlling combustion and a solid fuel including combustible matter and combustion controlling material co-operating with said holder to control the combustion of said combustible material.

110 2. A slow combustion heater comprising a body having restricted passageways through its sides and adapted to contain a slow burning material and means within the body for directing air of combustion and burnt gas throughout predetermined circuitous paths whereby to control the rate 115 of combustion.

120 3. A slow combustion heater comprising a body having restricted openings in its sides and adapted to contain the fuel being burned and means within the body for causing an indirect current of air to said fuel, thereby providing for preheating the air of combustion prior to its contact with the fuel.

125 4. A slow combustion heater comprising 130

a body having perforate side walls; a fuel support therein for containing the fuel said fuel support being imperforate and confining the air of combustion and the burnt gas 5 to a predetermined path throughout a part of the travel.

5. A slow burning heater comprising a body having perforate side walls and a fuel support imperforate throughout that part 10 of its length adjacent the perforations in the side walls whereby to preheat incoming air.

6. A slow burning heater comprising a body and a fuel support for the fuel located 15 within the body and means in said support for spacing the fuel from the body walls on all sides of said support.

7. In a slow combustion heater the combination of a body, a fuel support held in 20 place by contact with the walls thereof, said body and support providing air and gas passageways both without and within said support.

8. A slow combustion heater comprising a 25 body having restricted perforations through which air of combustion and burnt gas may pass and an elongated fuel support in said body, said fuel support being of elongated imperforate form and having inwardly extending ribs for spacing a fuel charge from 30 the walls of said body.

9. A slow combustion heater comprising a body, a fuel container therein of elongated form and means within the fuel container 35 for centering the fuel in the container and away from the walls thereof and away from the walls of the body.

10. A slow burning heater comprising a container body, a fuel support in said container body, a solid stick of fuel within said support and means for confining the air of combustion and the burnt gases to predetermined paths with respect to said stick.

11. A slow burning heater comprising an outer body or shell, a fuel support therein said support having ribs for maintaining a solid stick of fuel out of contact with the body of the support.

12. A slow combustion heater and a fuel therefor, said heater comprising a fuel holder for solid fuel, and an outer body hav-

ing air inlets and providing air passages for the air of combustion in contact with the fuel holder for preheating the air, and a solid fuel including combustible matter and 55 combustion controlling material in proportions for producing appropriate rate of combustion by the use of the air preheated in said holder.

13. A slow combustion heater and a fuel 60 therefor, said heater comprising a fuel holder for solid fuel, and an outer body having air inlets and providing air passages for the air of combustion in contact with the fuel holder for preheating the air, and a solid 65 fuel including combustible matter and combustion accelerating and retarding materials in proportions for producing appropriate rate of combustion by the use of the air preheated in said holder. 70

14. A slow combustion heater and a fuel therefor, said heater comprising a fuel holder for a solid fuel stick, and a container having perforations for admitting air of combustion and providing circuitous passageways in contact with the holder for preheating said air of combustion, and a solid fuel stick within said holder and providing combustion passages between said stick and said holder. 75

15. A slow combustion heater and a fuel 80 therefor, said heater comprising a fuel holder for a solid fuel stick, and a container having perforations for admitting air of combustion and providing circuitous passageways in contact with the holder for preheating said air of combustion, and a solid fuel stick within said holder and providing 85 a combustion passageway through said stick. 90

16. A slow combustion heater and a fuel therefor, said heater comprising a fuel holder for a solid fuel stick, and a container having perforations for admitting air of combustion and providing circuitous passageways in contact with the holder for preheating said air of combustion, and a solid fuel stick within said holder and providing 95 a combustion passageway through said stick and between said stick and said holder.

HENRY W. ALLPORT.
